(57) **CLAIM**

The ornamental design for a bottle as shown and described.

DESCRIPTION

FIG. 1 is a front perspective view of a bottle showing my new design;

FIG. 2 is an enlarged view of portion 2 shown in FIG. 1;

FIG. 3 is a front view of the bottle shown in FIG. 1;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a sectional view thereof taken along the lines of 9-9 from FIG. 1;

FIG. 10 is a front perspective view of the bottle, shown in use with an exemplary cap, wherein the cap is secured within the bottle top opening; and,

FIG. 11 is an exploded front perspective view of the bottle with the cap.

The dash-dash broken lines shown in the drawings are for the purpose of illustrating parts of the bottle as well as the designation of an enlargement view that form no part of the claimed design. The broken line showing of a cap in FIGS. 10–11 represents unclaimed environment. The dash-dot broken lines shown in the drawings illustrate a claim boundary.
